ABSTRACT

Fire extinguishing foam concentrate, compatible with sea water, comprises as active ingredient at least 10% by weight of a water soluble, surface active organo-silicon compound.

6 Claims, No Drawings

FIRE EXTINGUISHING FOAM CONCENTRATE

CROSS REFERENCE TO PRIOR APPLICATIONS

This is a continuation-in-part of application Ser. No. 197,477, filed Nov. 10, 1971, now abandoned, which in turn was a continuation of application Ser. No. 865,171, filed Oct. 9, 1969, and now abandoned.

FIELD OF INVENTION

The invention relates to fire extinguishing foam concentrates which contain surface active substances and, if desired, water. The fire extinguishing foam concentrate of the invention is particularly suitable for use with sea water.

BACKGROUND INFORMATION AND PRIOR ART

As is generally known, fires, particularly fires of fuels and propellants, are combatted by spraying foam in the form of continuous coats or coverings. Such foam blankets are also suitable for preventing the initial formation of fires.

Suitable prior art foaming agents for such purposes are prepared from protein salts, as for example from keratins, albumins, seed flour and the like which are modified by hydrolysis and stabilized with certain pre-selected metal salts.

However, as is wellknown in the art, foaming agents produced from protein hydrolysates cannot successfully be used for the combatting of certain types of fires. Thus, for example, such foaming agents are not suitable for fighting fuel fires or fires of polar substances as, for example, alcohol fires.

A further drawback of these known foaming agents resides in the fact that they are incompatible with dry fire extinguishing powders which are customarily used simultaneously, particularly if the powders have silicone containing surfaces. If such prior art foaming agents are used in conjunction with dry fire extinguishing powders, the foam has a tendency to collapse.

It has also recently been suggested to employ foaming agents which are water soluble, ion-active derivatives of a fluorocarbon- or a fluorosulfonic acid. Such compounds are usually applied in the form of an aqueous master solution. Concentrates of this kind have been described, for example, in German Patent 1,216,116. However, also the latter type of prior art foaming agents are not fully satisfactory. While it is true that such ion-active derivatives of fluorocarbon or fluorosulfonic acid are largely stable toward dry fire extinguishing powders, these foaming agents, however, cannot be foamed with hard water, particularly sea water. This, of course, limits the usefulness of the foaming agents to a considerable extent. This is so, because for combatting fires on ships, for example tankers, on the high sea, only sea water is available for preparing the foams. Accordingly, it is the primary object of the present invention to provide a fire extinguishing foam concentrate which, in addition to the beneficial properties of the prior art foaming agents, also exhibits compatibility and stability in respect to sea water and can be foamed with such water.

Concerning the prior art fluorocarbon tensides it should also be added that such tensides are extremely expensive since their manufacturing processes are exceedingly complicated. Accordingly, it is a further object of the invention to provide superior foaming agents

of the indicated kind which are relatively inexpensive to manufacture and have economical advantages not obtained by the prior art agents.

Finally it should be mentioned that the prior art fluor-containing tensides do not readily form stable aqueous foams of high expansion rates.

Accordingly, it is a still further object of the present invention to provide a foaming agent or concentrate of the indicated kind which has superior expansion rate properties as compared to the prior art compounds and which forms stable, aqueous foams.

SUMMARY OF THE INVENTION

In accordance with this invention it has surprisingly been found that the above objects are superiorly obtained if the fire extinguishing foam concentrate contains as active ingredient a water soluble, surface active organosilicon compound. Generally, the concentrate should contain between about 10 - 100% by weight of the active compound. The inventive concentrate, if it essentially consists of the active substance, may be used without any further additions provided the respective surface active organosilicon compound exhibits a suitable viscosity. If the inventive concentrate contains less than 100% by weight of active substance, then the remainder of the concentrate may be a suitable solvent such as, for example, water, a water miscible organic liquid, as for example ethanol, or mixtures of water and water miscible organic liquids.

The inventive concentrates are supplied in known manner to foaming devices, wherein a dense creamlike foam is produced with water. Experiments have indicated that, calculated on the amount of water used for producing the foam, advantageously 0.2 to 4% by weight of the organosilicon surface active compound should be used for producing superior fire fighting foams. The foam formed in this manner may be varied within wide limits in respect to its specific gravity. The water soluble surface active organosilicon compounds of the inventive foaming agents lend themselves for the production of highly expanding fire fighting foams.

In the event that the inventive fire fighting or extinguishing concentrate is provided in the form of an aqueous solution, then the pH of the solution should have an approximately neutral value. Preferred pH values are in the range between 7 and 9.

Water soluble polymers or polymer mixtures can be successfully employed in accordance with this invention which have the general formula I

wherein:

R^1 is alkyl, preferably lower alkyl of 1-4 carbon atoms, or $(CH_3)_3Si$;

$a = 0 - 5$;

$b = 1 - 3$;

R^2 is alkyl or aryl, preferably CH_3 or $(CH_3)_3SiO$;

R^3 is divalent hydrocarbon or $-O-$, preferably $-(CH_2)_3-$;

X is a hydrophilating group which may be anionic, cationic or nonionogenic; X is preferably $O_n-SO_3^-$

$\ominus$ Me $^\oplus$, wherein Me is an alkali-metal cation or, preferably, a substituted ammonium group; particularly preferred are ammonium groups which derive from oxethylated amines; $n = 0$ or 1 ; the ratio of the total number of Si-atoms per average molecule to b is equal to 2-5, the preferred ratio being 2.5-4; the total number of Si-atoms is preferably 2 to 7.

Those substances encompassed by formula I wherein $a \neq 0$, have to be prepared so that the final products do not contain contaminants of compounds of the formula

15

25

wherein $m \geq a$.

This is important because these contaminants have a defoaming action, particularly if siloxanols are involved. For this reason compounds of formula I could not successfully be used in the foam concentrates if they were to contain these contaminants.

A particularly preferred subgeneric group of compounds of the general formula I are those represented by the formula II:

45

In this formula:

$R^1 = (CH_3)_3Si$; up to 50 mole percent within a polymer mixture may be replaced by alkyl of 1-4 carbon atoms; preferred are compounds in which 5-25 mole percent of the $(CH_3)_3Si$ groups are replaced by alkyl;

$R^2 = CH_3$ or $(CH_3)_3SiO$;

$m = 1-3$, preferably 1-1.3;

$p, q, r = 0-7$;

$p + q + r = 1-20$, preferably 3-10.

Compounds corresponding to formula II can be readily prepared according to the teachings of German patent 1,179,937 if

65

is used as base. In doing so, products of formula II are mostly obtained wherein a predetermined proportion of the R^1 -groups are not $(CH_3)_3Si$ but rather alkyl of 1-4 carbon atoms. As previously stated, such products, wherein a portion of R^1 is constituted by alkyl of 1-4

carbon atoms are particularly suitable for the inventive purposes.

Compounds of formula I wherein $R^3 = -CH_2-$ and $X = -SO_3^\ominus Me^\oplus$ can be prepared according to the procedure disclosed in German Auslegeschrift 1,206,160 by reacting the corresponding vinyl-group containing siloxanes with $MeHSO_3$.

Other compounds which may be used for the purposes of this invention are generally represented by the following formula III

III

wherein:

$R^4 =$ alkoxy of 1-4 carbon atoms, $(CH_3)_3SiO$ or alkyl of 1-4 carbon atoms; alkoxy is preferred;

$R^5 =$ alkyl, hydrogen or $-(CH_2CH_2O)_{1-}H$, thus, for example $HN R_3^\oplus = NH(C_2H_5)_3^\oplus$, $HN(CH_2CH_2OH)_3^\oplus$ or $HN(i-C_3H_7)_3^\oplus$; and

$S = 2-5$.

Compounds of formula III may be prepared in a manner known per se as follows

One mole of siloxanols of the formula

is mixed with amines of the formula $NR_3^\oplus$ (2 or 4 moles and 5-20% of excess). The mixture thus obtained and 2 moles of organosilicon sulfates of the formula

45

wherein $R^6 = Cl$ or alkyl of 1-4 carbon atoms, are then synchronously added to an inert solvent in dropwise manner.

The organosilicon sulfates referred to may be prepared pursuant to the procedure disclosed in German patent 1,157,789.

The products thus obtained and if $R^6 = Cl$ are subsequently reacted with compounds of the formula R^4OH , for example, C_2H_5OH or $(CH_3)_3SiOH$, are separated from the solvent and, if necessary, filtered. If $R^6 = Cl$, then 4 moles of the amines of the formula $NR_3^\oplus$ are required plus an excess of 5-20%. By contrast, if $R^6 =$ alkyl, 2 moles of the amines of formula $NR_3^\oplus$ plus an excess of 5-20% are sufficient.

It should be added that other siloxanes than those of formulas I, II and III can be successfully employed within the scope of this invention. Thus, compounds of the following formula IV are very suitable

IV

wherein:

m , R^1 and R^2 have the meaning defined in formula II;
 R^3 = divalent hydrocarbon or

wherein

t = 1-3. The preferred R^3 groups are $-CH_2CH_2-$ and $-(CH_2)_3-$;

R^7 = hydrogen, alkyl or phenyl; and

n = 7-30.

Products corresponding to formula IV, wherein R^3 is divalent hydrocarbon, can be easily prepared by hydrosilating addition of the corresponding polyethers bearing olefinic terminal groups to the respective $SiH-$ group-containing siloxanes. Such a procedure has been disclosed in, e.g., Example 1 of U.S. Pat. No. 3,359,212.

By contrast, formula IV compounds wherein R^3 =

can be prepared in known manner by reacting polyethers of the formula

with corresponding siloxanes which latter contain $SiH-$, $SiCl-$ or SiO -alkyl groups. The interconnection between the polyethers and the siloxanes then takes place under splitting off H_2 , HCl or alkanol.

A still further group of siloxanes which is useful for the inventive purposes is symbolized by the formula V:

V 50

In this formula:

n , R^3 and R^7 have the same meaning as in formula IV;
 $S = 2-5$; and

R^8 = alkyl of 1-4 carbon atoms, preferably CH_3 .

Formula V compounds may be prepared in the same manner as the formula IV compounds, to wit, by hydrosilatingly forming an adduct of siloxanes of the formula

and polyethers with olefinic terminal groups or by reacting the siloxanes with polyethers of the formula

under splitting off of H_2 .

The last-mentioned polyethers may also be reacted in esterifying or reesterifying manner with siloxanes of the formula:

in which event HCl or alkanols are split off.

A still further siloxane system which has been demonstrated to be suitable for the inventive foam concentrates is represented by the formula VI:

VI

wherein

m , R^1 and R^2 are as defined in formula II;
 R^3 is divalent hydrocarbon, preferably $-CH_2-$ or $-(CH_2)_3-$;
 R^9 = hydrogen or alkyl;

Z is a halogen anion, except fluoride and preferably chloride.

However, Z need not be the anion of a halogen acid but can symbolize the anion of any other acid. Thus, Z may stand for acetate, formate, sulfate/2 etc.

Compounds of formula VI may be prepared as follows:

compounds of the formula

are reacted with amines or compounds of the formula

55 are reacted with amines or compounds of the formula

$S = 2-5$; and

R^8 = alkyl of 1-4 carbon atoms, preferably CH_3 .

Formula V compounds may be prepared in the same manner as the formula IV compounds, to wit, by hy-

60

drosilatingly forming an adduct of siloxanes of the formula

are reacted with acid of the formula ZH .

Such reactions are known in the art and have been disclosed in German Auslegeschrift 1,128,985 and by H. Maki, M. Komatsu and S. Komori, Kogyo Kagaku Zasski 70 (1967) 1771-4 (C.A. 68 (1968) 3865).

Yet another group which is suitable for use in the inventive foam concentrates is represented by the formula VII:

wherein R^8 and S have the meaning as in formula V; and R^3 , R^9 and Z are defined as in formula VI.

Formula VII compounds are produced by reacting compounds of the formula:

ity towards hard water, as for example, sea water. In order to test this characteristic, the so-called impact foam test was employed. A detailed description of the impact foam test is contained, for example, in the book by E. Manegold: Schaum, Strassenbau, Chemie und Technik-Verlagsgesellschaft m.b.H., Heidelberg, 1953, pages 97 and 98. In performing the test, a measuring cylinder with a diameter of 5.4 cm was used. The disc, used for the impact foam test, had a diameter of 5 cm and contained 87 holes with a diameter of 1 mm for each hole. The material to be foamed was filled into the measuring cylinder to a level of 3 cm and was thereafter foamed by moving the disc up and down for 40 times. The results which were obtained are tabulated in the following Table I.

TABLE I

with amines. In the alternative, compounds of the formula

may be reacted with ZH acids.

The preparation of the siloxanes which are used as starting substances may be effected either according to known methods by equilibration of the various siloxane building blocks or by cohydrolysis of the different silanes which participate in the formation, or by cocondensation of silanes and siloxanes in the manner described in the synthesis of the compounds of formula III.

Fire extinguishing foams produced from the foam concentrates described above exhibit the desired stabil-

The abbreviation HVT in the Table stands for half value time and indicates the time period which passed until an amount of liquid had been reformed which corresponded to one half of the original amount. The height of the foam was measured in millimeter.

height of the foam was measured in millimeter.

Table I clearly indicates that the inventive concentrate can be readily foamed with sea water and that the concentrate results in foams of larger expansion rates. The term "expansion rate" indicates the ratio of the foam volume to the volume of the original liquid. For comparison purposes, a fluorocarbon tenside, as it is commercially available and as it is used for fire extinguishing foam concentrates, was tested as seen in Table I.

60 Fire extinguishing tests were also carried out with the inventive fire extinguishing foam concentrates and with prior art concentrates. As combustible materials, normal gasoline, super gasoline and n-butanol were used. 100 cm³ of these liquids were in each case fed to a pot of a diameter of 14.5 cm. The liquids were then ignited and after a burning time of 2 minutes the extinguishing or fire combatting procedure was initiated.

65 The foam was produced according to the impact foam method with ordinary tap water and was sprayed in measured amounts onto the burning surfaces. The results are tabulated in the following Tables:

Tables IIa to IIc demonstrate the superior activity and effect of the inventive substances. In interpreting the Tables, it should be observed that the beneficial characteristics of the respective substance should be evaluated more favorable especially if the substance is used in smaller concentrations. Further, the expansion rates should be considered in the results.

The expansion rates are in the inventive substances 1 to 9 while in the comparison prior art substances the rate is only 1 to 4. Comparative extinction periods at higher expansion rates means, of course, increased economy of the concentrates. In order to consider all these factors, the Tables contain a column in which the amount of concentrates is indicated which was neces-

sary for extinguishing the fire within 15 seconds with the comparison test. The value for the 15 second extinguishing time, was extrapolated if not measured by tests.

Comparison tests were also carried out with a substance of formula II and those disclosed in Example 2 of the U.S. Busse Pat. No. 2,506,062, in Example 2 of the U.S. Busse Pat. No. 2,514,310, in Example 1 of the U.S. Busse Pat. No. 2,529,211, and in Example 43 of the U.S. Jackovitz Pat. No. 3,422,021. The respective foams were for this purpose prepared as described in connection with Table I. The test results are tabulated in Table III.

TABLE III

Foam Concentrate	Concentration in %	HVT in minutes	Expansion Rate	Extinguishing time required for Regular gasoline	Super gasoline	n-butanol
As disclosed in Example 2 of U.S. Patent 2,506,062 to Busse	2	5	1 : 7.7	no extinguishing effect	no extinguishing effect	no extinguishing effect
As disclosed in Example 2 of U.S. Patent 2,514,310 to Busse	2	12	1 : 3.3	no extinguishing effect	no extinguishing effect	no extinguishing effect

Product of formula II wherein m = 1; $\Sigma_{i=1}^3 pqr = 7.2$ $R^1 = (CH_3)_3Si$. 8 mole-% of $(CH_3)_3Si$ -groups are replaced by C_2H_5 -groups- $R^2 = CH_3$	2.0	8.0	1 : 9	12 seconds	10 seconds	3 seconds

The terms HVT and expansion rate as appearing in Table III have the same meaning as explained in connection with Table I. The fire extinguishing tests were performed as previously described in connection with Tables II. 60 grams of foam were used in each test and the burning substances were inherently difficult to extinguish. Table III clearly demonstrates that the silicone-tenside of formula II which was used as an example, exhibited significantly better fire fighting characteristics than the foams of Busse and Jackovitz. It follows that foam producing substances, although exhibiting surface tension lowering characteristics, are not necessarily suitable for fire fighting. It also follows that the inventive surface active compounds are superior to those of the comparison products.

What is claimed is:

1. In a fire extinguishing foam concentrate, the improvement which comprises that its active ingredient is a water-soluble, surface active organosilicon compound, said compound constituting at least 10 percent of said concentrate and having the formula

wherein

R^1 is $(CH_3)_3Si$;

R^2 is CH_3 or $(CH_3)_3SiO$;

40 $m = 1-3$;
 $p, q, r = 0-7$ and
 $p + q + r = 1-20$.

45 2. The improvement of claim 1, wherein the concentrate contains water.

3. The improvement of claim 1, wherein within a polymer mixture up to 50 mole percent of $(CH_3)_3Si$ are replaced by alkyl of 1-4 carbon atoms.

45 4. The improvement of claim 1, wherein $m = 1-1.3$ and $p + q + r = 3-10$.

50 5. The improvement as claimed in claim 1, wherein the concentrate essentially consists of at least 10 percent of said compound, the remainder being a solvent, said solvent being water and/or a water miscible organic liquid.

60 6. The improvement as claimed in claim 1, wherein the concentrate is in the form of an aqueous solution having a pH value of about between 7 and 9.
